(57) **CLAIM**

The ornamental design for a frame for a light, as shown and described.

DESCRIPTION

FIG. 1 is a front perspective view of a frame for a light, showing my design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top view thereof; and,

FIG. 7 is a bottom view thereof.

The broken lines shown in the drawings depict a portion of the environmental structure and a portion of the article that forms no part of the claimed design.

1 Claim, 4 Drawing Sheets
